(57) **CLAIM**

The ornamental design for an enclosure for customer premise device, as shown and described.

DESCRIPTION

FIG. 1 is a top view of an enclosure for customer premise equipment device, showing our new design;

FIG. 2 is a front elevation view of the enclosure for customer premise equipment device of FIG. 1;

FIG. 3 is a bottom view of the enclosure for customer premise equipment device of FIG. 1;

FIG. 4 is a rear view of the enclosure for customer premise equipment device of FIG. 1;

FIG. 5 is a right side elevation view of the enclosure for customer premise equipment device of FIG. 1; the left side elevation view of the enclosure for customer premise equipment device of FIG. 1 is a mirror image of the right side elevation view of the enclosure for customer premise equipment device of FIG. 1;

FIG. 6 is a top perspective view of the enclosure for customer premise equipment device of FIG. 1; and,

FIG. 7 is a bottom perspective view of the enclosure for customer premise equipment device of FIG. 1.

The broken lines in the drawings are for the purpose of

illustrating portions of the enclosure for customer premise equipment device that form no part of the claimed design.

1 Claim, 7 Drawing Sheets
